UNITED STATES PATENT OFFICE.

JAMES H. BAKER, OF SARATOGA SPRINGS, NEW YORK, ASSIGNOR TO BAKER AND SHEVLIN COMPANY, OF SARATOGA SPRINGS, NEW YORK, A CORPORATION OF NEW YORK.

PROCESS OF TREATING SULFITE, GROUND WOOD, OR OTHER PAPER-STOCK.

SPECIFICATION forming part of Letters Patent No. 735,444, dated August 4, 1903.

Application filed May 2, 1902. Serial No. 105,586. (No specimens.)

To all whom it may concern:

Be it known that I, JAMES H. BAKER, a citizen of the United States, residing at Saratoga Springs, in the county of Saratoga and State of New York, have invented an Improved Process of Treating Sulfite, Ground Wood, or other Paper-Stock, of which the following is a specification.

My invention relates to an economical, quick, and continuous method or process of screening and treating sulfite, ground wood, or other paper-stock, so as to recover all of the good stock that there is in the pulp.

Heretofore various methods or processes of treating and screening sulfite, ground wood, or other paper-stock have been employed; but the same have been attended with some difficulties or loss of time or lack of economy.

The object of my invention is to overcome these difficulties as far as possible.

In the process or method employed by me the supply of pulp carrying the fiber and a supply of water to reduce the consistency thereof are each regulated and delivered into a suitable mixing-chamber or flow-box, from which the materials pass to a centrifugal device, in which such material is rapidly and forcefully agitated and thrown against screen-plates, which separate the good stock from the slivers, the good stock passing through the screen-plates into a receptacle and being delivered from one side thereof and the slivers remaining on the opposite side of the screen-plates and received into a receptacle, from which they are delivered. In this part of the process a cleaning device is occasionally made use of, and a water-spraying device is also occasionally made use of for cleaning the screen-plates, so as to keep the apertures therein free and clear for use, and a part of the method consists in passing currents of air through the centrifugal device to facilitate the action thereof and assist in the separation of the fibers from the pulp more perfectly than heretofore. These currents of air are created by the centrifugal devices themselves, and to insure the action of these currents of air the machine is so constructed as to provide an exit for the air beyond the location of the screen-plates, and

which device is adapted for conjoint action with the cleaning device for spraying the plates. The action of the centrifugal devices draws in the air and forces the same against the screen-plates, with the pulp that is thrown against said plates, with force, and the air passes through the screen-plates and escapes between the screen-plates and the casing through openings provided in the cover of the centrifugal device. The action of the air is to segregate and separate the pulp into minute portions and to force the fiber through the screen-plates, where the same is collected in receptacles provided therefor. The good stock or fiber is delivered from the receptacles containing the same into a suitable receptacle outside of the centrifugal device and from there by a pipe into a suitable pulp-vat, in which vat is a couch-roller for gathering the pulp. From this roller the pulp is delivered upon an endless felt belt forming part of a machine known as a "wet" machine and by said belt to a roller of the machine, on which said pulp is collected and is put under pressure as the same accumulates. Meanwhile in the process the slivers are delivered from the receptacle receiving the same and preferably mixed with an additional supply of water to give the same a good wash, and from there the slivers or tailings pass into a diaphragm-screen and are therein subjected to agitation, which causes a final and more perfect separation of the particles, so that any good stock remaining or that may be caught or availed of is delivered through said screen in one direction and the slivers or waste stock delivered by a suitable device from the machine in a different direction.

I have discovered that in carrying out this method and in the employment of suitable machines therefor one centrifugal machine is adapted for preparing the materials for several wet-machines and several diaphragm-screen machines, so that these latter machines may be arranged in groups.

In the drawings I have represented, in Figures 1 and 2, disconnected diagrammatic elevations of a centrifugal pulp-screen, a wet-machine, and a diaphragm-screen machine, and

the connected supporting and coöperating parts suitable for the carrying out of my improved process; and Fig. 3 is a vertical section through the improved form of centrifugal gal-screen forming part of the device employed by me in carrying out the present process.

The apparatus preferred by me in the carrying out of the improved process described 10 herein comprises a centrifugal pulp-screen *a* similar to the devices shown and described in Letters Patent No. 686,962, of November 19, 1901, and No. 693,215, of February 11, 1902. 15 *a'* is a pulley mounted on a shaft, and *a''* a belt on an adjacent pulley for imparting rotation to the centrifugal device.

b represents a wet-machine similar to that described and illustrated in Letters Patent No. 639,882, granted December 26, 1899, and 20 *c* represents a diaphragm or tailings screen, which may be of any good construction, but preferably is substantially the same as that shown and described in Letters Patent No. 682,839, granted September 17, 1901.

25 Referring to the drawings, 2 is a pipe for water, and 3 a valve for regulating or gaging the supply thereof. 4 is a pipe for paper-stock, and 5 a valve for regulating or gaging the supply thereof. The water and the 30 paper-stock are delivered from these pipes into a vat 6, where they are mixed, and from this vat the materials are delivered past an adjustable gate 7 into pipes 8 to the centrifugal machine. In the centrifugal machine the 35 rapidly-rotating devices take up the material and force it against the perforated screen-plates *k*, the good fiber or stock passing through the perforations of the screen-plates to the outside and between the same and the 40 outer casing *l*, and the slivers or tailings remain on the inside of the screen-plates, the good stock falling into the trough *g* and the tailing or slivers into the trough *h*.

The rapid rotation of the centrifugal devices sets up currents of air of force, projecting the same against the screen-plates, the 45 action of which is to assist the screening operation in insuring the passage of the good stock of fibers through the screen-plates, and 50 to insure this action and provide a vent or escape for the pent-up air between the screen-plates and the outer casing removable perforated gratings *e* are employed in the top of the machine.

55 In the screening operation it is essential that periodically the screen-plates be cleansed, and for this purpose a cleaning device *d* in a ring-like form and bearing against the inner surface of the screen-plates and actuated by 60 rods extending outside of the machine is employed. This device may be moved from its uppermost normal position of rest down to the lower edge of the screen-plates in removing the slivers from the surface, and a water- 65 spraying device 9, controlled by hand, may be inserted through the openings in the top of the machine upon the removal of the per-

forated gratings *e*, so as to force water against the outer surface of the screen-plates to wash down the good stock or fibers and cleanse the 70 perforations, forcing any materials that may be in the openings of the screen-plates into the machine and down into the sliver-trough.

The supply-trough 10 receives the good stock from the trough *g* of the centrifugal device, delivers the same through the pipe 11 to the pulp-vat 12, forming a storage device thereof for one or more wet-machines *b*. In this pulp-vat there are one or more couch-rollers 13 for taking up the pulp as rotated 80 and delivering the same upon the felt belt 14 of the wet-machine, upon which belt the paper-stock fiber is conveyed to the roller 15. The felt belt 14 passes around a roller below the roller 15, but the upper roller gathers the 85 pulp upon it, and pressure exists between the two rollers while the pulp gathers, and periodically this pulp is removed from the roller 15 in the usual manner.

The slivers from the trough *h* are preferably mixed with a supply of water to provide a good wash, and the water so mixed may come from one or two sources. The hollow base *f* of the centrifugal machine is to be filled with water for cooling purposes, the same being supplied by a pipe *f'*. Said water is conveyed away from the hollow base by a pipe *f''*, that enters the sliver-trough, so that the water employed for cooling purposes is also mixed, as a part of the process, with the slivers in the sliver-trough *h*. The slivers or tailings pass from the trough *h* into a discharge-trough 16, and in cases where the water employed for cooling the hollow base of the machine is not passed into the sliver-trough a pipe 17 may enter the discharge-trough 16 to mix a regulatable quantity of water with the slivers or tailings, so as to reduce the consistency of said slivers or tailings for the after action of one or more diaphragm-screen devices *c*.

I prefer to add to the diaphragm-screen structure shown and described in Patent No. 682,839, of September 17, 1901, endless chains 18, passing around sprockets upon shafts 20 at opposite ends of the machine, and to connect to these chains scraper-blades 19, of any desired construction, and to revolve these shafts, sprocket-wheels, and chains by a shaft 21, having a worm-wheel engaging a pinion on the shaft 20, and a pulley engaged by a belt 22, passing around the main pulley-shaft 23. The action of this device is to cause the scraper-blades 19 to pass through the machine in one direction immediately above the plates *c'* of the diaphragm-screen and remove from the machine at one end the tailings or slivers progressively, permitting a thorough action of said plates upon the mass to remove therefrom any good fiber or stock in recovering the same. This good stock is taken care of as provided for in the Patent No. 682,839.

In carrying out my method or process by the devices hereinbefore described the paper-stock or similar material to be treated is prop-

erly diluted, regulated, agitated, separated, and thereafter treated for the utilization of the good stock, and further treated for the final separation of any good stock from the 5 slivers or tailings, all in a thoroughly quick and efficient manner and in maximum quantities to an extent and thoroughness not heretofore attained.

I claim as my invention—

- 10 1. The process herein described of treating sulfite, ground wood or other paper-stock for the separation and recovery of the good fibers from the tailings or slivers and formation of the same into sheets, consisting in mixing 15 regulatable and predetermined quantities of paper-stock and water, agitating the mass and separating the good fibers from the slivers, mixing water with the slivers or tailings to reduce the consistency thereof, agitating 20 the mass and separating therefrom any remaining good fibers and conveying away and forming the good fibers into a compressed sheet.
- 25 2. The process herein described of treating sulfite, ground wood or other paper-stock for the separation and recovery of the good fibers from the tailings or slivers and the formation of the same into sheets, consisting in mixing 30 regulatable quantities of paper-stock and water, agitating the mass and separating the good fibers from the slivers, and simultaneously causing forceful currents of air to act upon 35 the mass in its agitated condition to assist in the separation of the particles, mixing water with the slivers or tailings to reduce the consistency thereof, agitating the mass and separating therefrom any remaining good fibers and thereafter forming the good fibers into a compressed sheet.
- 40 3. The process herein described of treating

sulfite, ground wood or other paper-stock for the separation and recovery of the good fibers from the tailings or slivers and formation of the same into sheets, consisting in mixing regulatable quantities of paper-stock 45 and water, agitating the mass and separating the good fibers from the slivers and periodically employing jets of water for assisting a continuous operation and during the separation of the good fibers from the slivers, mixing water with the slivers or tailings to reduce the consistency thereof, agitating the mass and separating therefrom any remaining good fibers and conveying away and forming the good fibers into a compressed sheet. 55

4. The process herein described of treating sulfite, ground wood or other paper-stock for the separation and recovery of the good fibers from the tailings or slivers and formation of the same into sheets, consisting in mixing 60 regulatable quantities of paper-stock and water, agitating the mass and separating the good fibers from the slivers, simultaneously causing forceful currents of air to act upon the mass in its agitated condition to assist 65 in the separation of the particles and periodically employing jets of water for assisting a continuous operation and during the separation of the good fibers from the slivers, mixing water with the slivers or tailings to 70 reduce the consistency thereof, agitating the mass and separating therefrom any remaining good fibers and conveying away and forming the good fibers into a compressed sheet.

Signed by me this 26th day of April, 1902. 75

JAMES H. BAKER.
